US0D1000109S

(12) United States Design Patent (10) Patent No.: US D1,000,109 S
(45) Date of Patent:  Oct. 3, 2023

(54) HANDBAG

(71) Applicant: STEEL AMERICAN LUXURY LLC,
Winnetka, IL (US)

(72) Inventor: Nicole Steel, Winnetka, IL (US)

(73) Assignee: STEEL American Luxury LLC,
Winnetka, IL (US)

() Term: 15 Years

(21) Appl. No.: 35/003,019

(22) Filed: Mar. 29, 2022

(80) Hague Agreement Data

Int. Filing Date: Mar. 29, 2022

Int. Reg. No.: DM/220597

Int. Reg. Date: Mar. 29, 2022

Int. Reg. Pub. Date: May 13, 2022

(51) LOC (14) Cl. 03-01

(52) U.S. Cl.

USPC D3/243

(57) CLAIM

The ornamental design for a handbag, as shown and described.

DESCRIPTION

1. Handbag

1.1 : Perspective

1.2 : Front

1.3 : Back

1.4 : Right

1.5 : Left

1.6 : Top

1.7 : Bottom

The figures include surface shading, which represents contour and not surface ornamentation; The areas shown with stippling in the figures represents a contrast in materials from the areas shown without stippling; The broken lines contained within stippled areas represent stitching and form no part of the claimed design.

1 Claim, 7 Drawing Sheets
